UNITED STATES PATENT OFFICE.

WILLIAM SCHWEIKERT, OF BROOKLYN, NEW YORK.

BUILDING STRUCTURE.

1,014,416.

Specification of Letters Patent.

Patented Jan. 9, 1912.

Application filed April 28, 1909. Serial No. 492,678.

To all whom it may concern:

Be it known that I, WILLIAM SCHWEIKERT, a citizen of the United States, and a resident of Brooklyn, Kings county, New York, have invented certain Improvements in Building Structures, of which the following is a specification.

This invention relates to certain improvements in building structures, and more particularly in that class of structures wherein the walls, partitions, etc., are provided with attached facings formed from molded cement, concrete or other plastic substance, and the object of the invention is, in part, to 10 provide a facing slab or block of novel and improved construction capable of advantageous employment in such structures, and in part, to provide means of a simplified and improved character for holding such slabs or blocks in position upon the frame work of the structure, whereby the said slabs or blocks may be conveniently and quickly applied in position for use, and are supported with greater security when so applied.

25 The invention consists in certain novel features of the construction, and combinations and arrangements of the several parts of the facing slabs or blocks and of such attaching means therefor, whereby certain important 30 advantages are attained and the structure is rendered simpler, less expensive, and otherwise better adapted and more convenient of erection and use, all as will be hereinafter fully set forth.

35 The novel features of the invention will be carefully defined in the claims.

In order that my invention may be the better understood, I will now proceed to describe the same with reference to the accompanying drawings, wherein—

Figure 1 is a partial side elevation showing the wall of a structure embodying my improvements; Fig. 2 is a horizontal sectional view taken transversely through the 45 wall shown in Fig. 1, the plane of the section being indicated by the line *a—a*, in Fig. 1; Fig. 3 is a perspective view showing the outer part of a slab or block embodying my improvements; Fig. 4 is a perspective view 50 similar to Fig. 3, but showing the rear part of the facing slab or block; Fig. 5 is an enlarged fragmentary section taken through an edge portion of one of the slabs or blocks; Fig. 6 is an enlarged fragmentary 55 section taken through the edge portion of one of the slabs or blocks in the plane indi-

cated by the line *b—b*, in Fig. 5; Fig. 7 is a detail view drawn to an enlarged scale and showing a bonding or anchoring device for holding the slabs or blocks in relation, and 60 Fig. 8 is a vertical section taken through the wall of a structure and showing certain features of construction to be hereinafter referred to.

Referring first to Figs. 1 and 2, the wall 65 of the structure is formed from two series 1, and 2, of their slabs or sections which are molded from cement, concrete, or other suitable plastic material in sizes and contours such as are desirable to adapt the slabs or 70 sections of the respective series for use as facings for the inner and outer surfaces of the walls of the structure. For this purpose, the exposed surfaces of said slabs or sections may be ornamented or molded in any appropriate design or may be made plain or smooth, as may be desired. The slabs or 75 sections 3, 3 of the respective series comprised in the facings 1 and 2 are adapted to be rested one upon another and edge to edge 80 in a well known way, so as to produce such facings for the wall of the structure, and to facilitate their setting, each slab or section will, by preference, be provided with 85 tongues 4, 4 extended along one vertical and one horizontal edge, the other vertical and horizontal edges of such slab or section having grooves 5, 5 wherein are adapted to be accurately received the tongues 4, 4 at the contracting edges of adjacent slabs or sections. In setting the slabs or sections 3, 3 to 90 form the facings 1 and 2 for the outer and inner surfaces of the wall of the structure, the said slabs or sections are arranged in horizontal courses in a well known way, and 95 the joints between the slabs or sections of each course are midway between those of the subjacent and superjacent courses so as to be overlapped thereby.

As shown in the drawings, the several 100 slabs or sections 3, 3 are provided with attaching means, which are herein shown as made in the form of metallic plates or members 6, 6 embedded within the plastic substance during the manufacture of the slabs 105 or sections and having parts 7, 7 exposed at the surfaces of said slabs or sections in position for convenient engagement with securing or anchoring devices whereby the slabs or sections may be conveniently held 110 in relation during their application to the structure. In certain cases it will also be

desirable to provide the slabs or sections with embedded reinforcements such, for example, as is shown at 8 in Figs. 5, 6 and 8, and where such reinforcements are provided 5 I prefer to connect the attaching means either integrally or otherwise, to said reinforcements so as to afford increased security. In the drawings I have shown the reinforcements formed from wire netting, although 10 simple wires or metal strips may also be used with good results, and I have shown the attaching means as formed of metallic plates each of which has one end provided with divergent arms 9, 9 which are interlocked in the mesh of the wire netting 8, and have serrations 10, 10 capable of engagement with the netting, the extremities of the arms being herein shown as bent to produce hooks or loops 11 which are engaged with 15 the netting to afford a secure connection of the parts prior to molding of the slabs or sections.

The reinforcements 8, 8 are usually embedded in the slabs or sections at points central of their thickness, and in the drawings 20 I have shown the attaching plates 6, 6 so positioned that their parts 7, 7 are exposed at the edges of the slabs or sections whereat the tongues 4, 4 are produced, the proportions being such that the parts 7, 7 of the 25 attaching plates do not project beyond the outer surfaces of the tongues 4, 4, in order to lessen the liability of bending or loosening of the attaching plates after molding 30 of the slabs or sections and during transportation, and said exposed parts 7, 7 of the attaching plates are bent over laterally as shown at 12 on the drawings, so as to stand out of line with the tongues 4, 4, and in substantial alinement with the inner surfaces of 35 the slabs or sections so as to be adapted to fit accurately against the studding or framing of the structure, as shown in Fig. 8 when the slabs or sections are to be attached 40 thereto.

The projecting exposed parts 7, 7 of the several slabs or sections 3, 3 are apertured, as shown at 14 for the passage of nails, screws or other suitable fastenings by means 45 of which the said slabs or sections may be securely held in relation when applied to the walls, partitions, etc., of the structure, and the tongues 4, 4 are recessed or cut away opposite to each such projecting exposed part 50 7 so as to afford convenient access thereto for the application of such fastenings. The grooved edge portions 5, 5 of each of the several slabs or sections are also recessed or 55 cut away upon the inner surface of such slab or section, as clearly shown at 16 upon the drawings, so as to permit of receiving the said projecting exposed parts 7, of adjacent slabs or sections when applied in position over the tongues 4 of such adjacent 60 slabs or sections, as shown in Fig. 8.

In the practical employment of my improvements, the slabs or sections constructed as above described may be applied to the walls, partitions, etc., of the structure in various ways. For example, when the structure has a wooden frame, the slabs may be applied at opposite sides of the studding and held thereto by means of nails, screws or the like, driven through the perforations 14 of each attaching plate into such studding, the arrangement of the parts being such that the projecting parts 7 of said attaching plates are adapted to fit flush against the studding and the grooved edge portions 5 of the slabs interlocking with the tongues 4, 4 of adjacent slabs so as to produce tight joints within which the parts 7 are concealed, and affording a secure connection of the grooved edges of the slabs to the studding. Where desired the slabs or sections may also be employed in that class of structures the walls of which are molded homogeneously from concrete or the like, the apertured parts 7 serving to receive the ends of tie rods or bonds 17 which are screw-threaded 70 to receive nuts 18, 18 at their opposite ends between which the said projecting parts 7 are securely held, the said rods or bonds 17 being of such length as to hold the slabs or sections in spaced relation, as shown in Fig. 75 1 2 so as to produce a mold which may be filled with concrete or a similar plastic filling 19 adapted upon hardening, to unite the facings 1 and 2 in such a manner as to produce a substantially homogeneous wall of 80 great strength. This use of my improvements is particularly advantageous, since it permits of erecting the walls without the employment of costly scaffolding or mold sections, the nuts 18 being capable of adjustment to regulate the spacing of the facings as may be desired for plumbing the walls or giving batter thereto, and the molded nature of the slabs affording any desired treatment or ornamentation at a minimum of expense and labor.

For thin partitions, and especially where such partitions are employed in fire proof construction, my improvements are particularly well adapted for use. In such circumstances channel irons 20, are usually erected, as shown in Fig. 8 in lieu of studding, and the slabs or sections 3, 3, which may for such use, be made extremely thin, are applied to the opposite sides of said channel irons to 90 produce the facings 1 and 2, and are held in relation by means of bolts or screws 21, 21 applied through the apertures 14 of the attaching plates and engaged with the flanges of said channel irons.

From the above description of my invention it will be seen that the building structures embodying my improvements are of an extremely simple and comparatively inexpensive nature and are particularly de- 95 100 105 110 115 120 125 130

sirable by reason of the convenience and speed with which they may be erected, and it will also be obvious from the above description that the structure is susceptible of some modification without material departure from the principles and spirit of the invention, and for this reason I do not desire to be understood as limiting myself to the precise formation and arrangement of the several parts herein set forth in carrying out my invention in practice.

Having thus described my invention, what I claim and desire to secure by Letters Patent is:

15. 1. A facing slab formed from molded plastic material, having a reinforcement embedded in it and provided with a projecting tongue extended along one edge portion and an attaching device having longitudinally divergent arms embedded in said slab and connected by means of the arms with the reinforcement within the same and provided with a part projecting from the edge of the slab and adapted for engagement with a fastening device.

20. 2. A facing slab formed from molded plastic material having a reinforcement embedded in it, and provided with a projecting tongue extended along its edge portion and having recesses at intervals, and an attaching device having longitudinally divergent arms embedded in said slab and connected with the reinforcement within the same, and provided with a part projecting from the edge of the slab in alinement with recesses in the tongue thereof, and adapted for engagement with a fastening device.

3. A facing slab formed from molded plastic material having a reinforcement embedded in it, and an attaching device having serrations engaged with the reinforcement within the slab and having a part projecting from the slab for engagement with a fastening device. 40

4. A facing slab formed from molded plastic material, having a reinforcement embedded in it and an attaching device having longitudinally divergent arms embedded in said slab, the free ends of the divergent arms being formed into loops which engage the reinforcement within the slab, said attaching device having a part projecting from the slab for engagement with a fastening device. 45

5. A facing slab formed from molded plastic material having a reinforcement embedded in it and provided with a projecting tongue extended along its edge portion having recesses at intervals and an attaching device having longitudinally divergent arms embedded in said slab and connected with the reinforcement within the same, and provided with a part projecting from the edge of the slab in alinement with the recess in 60 the tongue thereof and adapted for engagement with a fastening device, said projecting part being disposed out of alinement with the longitudinally divergent arms. 65

In witness whereof I have hereunto signed my name, in the presence of two subscribing witnesses.

WILLIAM SCHWEIKERT.
